UNITED STATES PATENT OFFICE.

ROYCE L. BEERS, OF DETROIT, MICHIGAN, ASSIGNOR TO DETROIT STOKER COMPANY, OF DETROIT, MICHIGAN, A CORPORATION OF MICHIGAN.

UNDERFEED STOKER.

Application filed October 15, 1923, Serial No. 668,747. Renewed January 8, 1927.

This invention relates generally to stokers and refers more particularly to multiple retort stokers of the so called side dump type.

One of the essential objects of the invention is to provide a stoker of this character having mechanism for shifting the fuel laterally over the retorts whereby the consumed fuel and ash will be positively discharged onto suitable ash receivers at the opposite 16 sides of the furnace.

Another object of the invention is to provide a stoker of the above mentioned character having the tuyères thereof arranged in a common plane whereby with a given 15 head space a greater combustion space is obtainable resulting in a more complete combustion of the fuel and consequently greater efficiency in operation.

Another object of the present invention 20 is to provide an underfeed stoker of the multiple retort, side dump type, in which a uniformity exists between the several retorts and between the several tuyères so that it will be practical to carry fewer replacement 25 parts owing to the fact that an extra retort or tuyère is interchangeable with any of the retorts and tuyères in use and consequently may be used as a replacement for any one of these parts in use which may become 30 broken or otherwise incapacitated. This is particularly advantageous as it effects an economy not only in manufacture but in maintenance.

Another object of the present invention is 35 to provide a stoker having the tuyères arranged in a common plane but having certain areas of the walls of the retorts or tuyères or of the retorts and tuyères so shaped as to laterally shift or direct the fuel toward the 40 side dump plates or ash receivers without any movement of the tuyères relatively to the retorts.

A further object is the provision of adjusting means wherein the discharge may be 45 varied to obtain a more uniform consumption of fuel and the maintenance of a fuel bed of the desired form.

Another object is to provide a stoker that is simple in construction, efficient in operation, inexpensive to maintain and economical in the use of fuel.

With the above and other objects in view, the invention consists in certain novel features of construction, combination and arrangement of parts as will be more fully de-

scribed and particularly pointed out in the appended claims.

In the accompanying drawings:

Figure 1 is a front elevation of a stoker embodying my invention; 60

Figure 2 is a longitudinal sectional view through the stoker;

Figure 3 is a cross sectional view through the furnace and stoker mechanism;

Figures 4 and 5 are views similar to Figure 3 but showing fewer retorts; 65

Figures 6 and 7 are views similar to Figures 4 and 5 but showing slightly modified constructions.

For the purpose of illustration, I have 70 shown and will describe a specific form of stoker as an embodiment of my invention, but do not desire to be limited to the same, as it will be obvious that other forms could be employed and various modifications made 75 without departing from the spirit of the invention.

The numeral 1 designates a plurality of laterally spaced horizontal retorts into which the green fuel is fed from suitable hoppers 2 supported in front of the furnace upon casings 3 in alignment with the retorts. The green fuel may be supplied by any suitable means (not shown) to the hoppers and is preferably fed into the retorts by suitable 80 rams 4 mounted in the casings 3. These rams are reciprocated by pitman rods 5 connected to a rotary crank shaft 6 in front of the furnace by means of blocks 7 rotatively mounted on certain cranks of the shaft and 85 adjustably mounted upon the pitman rods. The shaft is suitably journaled in a frame 8 secured to the front wall 9 of the furnace and is driven from suitable transmission mechanism (not shown) housed within a 90 casing 10 upon the frame. 95

The fuel is advanced in the retorts by usual pusher blocks 11 mounted upon and actuated by suitable rods 12 connected to the forward ends of the rams 4 so as to be 100 actuated thereby.

In a stoker of the type specified, it is essential for its proper operation that the ash be wholly and uniformly discharged without loss of fuel and to accomplish this result, I 105 have provided means whereby the fuel may be shifted gradually while the stoker is in operation, in the direction of the ash receivers so that as the latter are approached only the ash will be deposited thereon. The fuel 110

shift may be effected by hand or automatically, either mechanically or by reason of the shape of the retorts or tuyères, or both, as will be described and I preferably provide 5 for an adjustment for the fuel shifting mechanism whereby the discharge of ash may be varied as occasion may require.

For moving the fuel bed laterally automatically mechanically so that the consumed 10 fuel and ash will be deposited upon the ash receivers 15 at the opposite sides of the furnace, I provide a plurality of air tuyères 16 which are preferably shiftable transversely over the retorts. Each series of 15 tuyères are formed of short units 17 of standard construction that have air openings 18 in the inclined sides thereof and are clamped together in an end to end relation. The intermediate series of tuyères are slidably 20 mounted upon flanges 19 projecting laterally from the upper edges of the retort, while the outer series of tuyères are slidably mounted upon flanges 20 extending laterally from the outer walls of the outer retorts as 25 well as upon horizontal side plates 21 overhanging the ash receivers 15. To prevent binding of the tuyères, I preferably provide lugs or projections 20' at the bottom of the tuyère for spacing the latter from the flanges 20 and plates 21. These projections are in a comparatively cool part of the tuyères and should not expand as much as would the top and hot part thereof.

From the description of the construction thus far it will be apparent that the 35 retorts are of a substantially uniform construction and furthermore that the tuyères are also a uniform construction and are arranged in a common plane. By arranging 40 these tuyères in this manner a greater combustion space above the tuyères is obtained which results in a more complete combustion of the fuel and consequently in a greater efficiency. Furthermore, the uniformity in the retorts and tuyères permits 45 of an economy in manufacture and maintenance as was previously pointed out.

For shifting the tuyères simultaneously, I provide a plurality of rock arms 22 that 50 are connected to the tuyères and that are mounted upon and actuated by suitable rock shafts 23 extending longitudinally of the furnace between the retorts. These shafts extend through the front wall 9 of the 55 furnace and are connected at their forward ends to suitable rock arms 24 projecting upwardly between a pair of spaced parallel bars 25 extending across and in front of the hoppers 2. The arms 24 are provided with 60 spaced openings at the upper ends thereof that receive pins 26 upon which suitable rollers 27 are mounted for supporting the bars 25 and are adjustably connected to the bars 25 by means of removable pins 28 that 65 may be adjusted upon opposite sides of the

arms into spaced aligned openings 29 in the bars. Thus, the lateral movement of any of the tuyères may be easily and quickly varied as desired to take care of irregular conditions of the fire bed. If desired, the 70 pins at the opposite sides of any of the rock arms 24 may be removed entirely so that the tuyères actuated thereby will be permitted to remain idle while the other tuyères are being moved.

For reciprocating the bars 25 to actuate the rock arms 24, I provide another rock arm 30 that is connected to the bars 25 at one end thereof and that is non-rotatively secured to a stub shaft 31 journaled in the 80 frame 8. In order that the same driving means may be used for both the rams 4 and the tuyères 16, the stub shaft 31 is driven from the crank shaft 6 by means of a rotary cam 32 non-rotatively secured to the shaft 8 and having an inclined face 33 that is adapted to be alternately engaged by the parallel arms 34 of a U-shaped member 35 non-rotatively secured to the stub shaft 31.

In use, rotation of the crank shaft 6 will 90 impart a reciprocatory movement to the rams 4 and rods 12, which will cause the periodic feeding and advancing of the fuel in the retorts. Rotation of the crank shaft 6 will also cause the reciprocation of the bars 25 which in turn will rock the arms 24, shafts 23 and arms 22 and will cause the tuyères 16 to slide transversely so that the consumed fuel and ashes will be moved over 95 the side plates 21 and onto the ash receivers 100 15.

From the foregoing description it will be readily apparent that a positive discharge of the consumed fuel and ash upon the ash receivers is obtained and that by reason of the gradual and uniform discharge the wasting of green fuel is obviated. It will be further noted that through the adjustability of parts, not only may the discharge 105 be varied to suit the particular requirements, but any one of the series of tuyères may be made active, in some instances only one movable tuyère being required to accomplish 110 the desired results.

In Figures 6 and 7 of the drawings a 115 slightly modified form of construction is illustrated in which the fuel may be shifted laterally toward the ash receivers, automatically, but without positive mechanical means 120 for accomplishing this. In this form of construction the inner walls 36 of the two retorts shown in Figure 6, or of the outer retorts shown in Figure 7, are arranged in a substantially vertical plane while the outer walls 38 of the said retorts are inclined upwardly and outwardly toward the ash receivers 15. It will furthermore be noted 125 that the walls of the tuyères 16 adjacent to the inclined retort walls 38 constitute a substantial continuation thereof, being inclined 130

on an angle substantially coincident therewith. With this form of construction the fuel as it is pushed through the retorts is directed by the inclined surfaces of the retorts or tuyères, or both, laterally toward the ash receivers so as to ultimately cause a discharge of the consumed fuel upon the ash receivers without the use of any mechanical impelling means. It will be apparent that by the proper arrangement of the said inclined surfaces that the fuel will be directed laterally in opposite directions toward the adjacent or adjoining ash receivers. Obviously with this construction the tuyères may either be rigidly fixed in position or if movable may be left at rest in their position as illustrated in Figures 6 and 7 of the drawings. Obviously with this construction of retort if movable tuyères are also employed the fuel may be more readily pushed toward the ash receivers.

What I claim as my invention is:—

1. In a furnace, an ash receiver at one side thereof, a retort adjacent to one side of said ash receiver, and an air tuyère extending longitudinally of the retort supported along a longitudinal edge by a longitudinal wall of the retort, said tuyère being movable transversely of the retort along the said point of support for shifting consumed fuel laterally onto said ash receiver.

2. In a stoker, an ash receiver, a plurality of retorts located to one side of said ash receiver, the retorts being in a common horizontal plane, and a plurality of air tuyères slidably supported upon adjacent walls of adjacent retorts and adapted to be shifted transversely above said retorts for causing travelling of the fuel bed laterally for effecting a discharge of ash onto the ash receivers.

3. In a stoker, the combination with a retort for fuel, a fuel feeding ram in alignment with the retort, and an actuating connection for said ram comprising a rotatable crank, a pitman connected to the ram, and a block adjustably connected to the pitman and pivotally connected to the crank, of an ash receiver at one side of the retort, an air tuyère adapted to be shifted above said retort for effecting a discharge of ash onto said ash receiver, and means operated by said crank for shifting said tuyère.

4. In a stoker, the combination with a retort for fuel, a fuel feeding ram in alignment with the retort, and an actuating connection for said ram comprising a rotatable crank, a pitman connected to the ram, and a block adjustably connected to the pitman and pivotally connected to the crank, of an ash receiver at one side of the retort, an air tuyère adapted to be shifted above said retort for effecting a discharge of ash onto said ash receiver, a rock shaft, rock arms con-

nected to said shaft, one being adapted to shift said tuyère, a reciprocating member connected to the other arm, and means operated from said crank for reciprocating said member to rock said arms and cause said tuyère to be shifted.

5. In a stoker, a retort for fuel, an air tuyère movable above the retort, a rock shaft, rock arms connected to said shaft, one arm being adapted to move the tuyère relative to the retort, a reciprocating member connected to the other arm, a rock arm connected to said member, a shaft connected to the last-mentioned rock arm, a U-shaped member carried by the last-mentioned shaft, a rotary crank, and a cam upon the crank having an inclined face alternately engageable by the arms of said U-shaped member for rocking the last-mentioned shaft and arm to reciprocate said member and cause the first-mentioned arm to be rocked.

6. In a furnace, the combination with a series of parallel retorts extending longitudinally of the furnace, of ash receivers at the opposite sides of the furnace for receiving the consumed fuel from said retorts, tuyères bridging the spaces between said retorts, and arranged in horizontal alignment and means for shifting said tuyères transversely of said retorts for transferring the consumed fuel laterally of said retorts to said ash receivers.

7. In a furnace, a fuel bed support comprising a series of parallel retorts extending longitudinally of the furnace, adjacent retorts being spaced apart to provide passage of air upwardly between adjacent longitudinal walls of adjacent retorts from a point below the fuel bed, ash receiving means extending longitudinally of the furnace adjacent the outermost of said retorts, tuyères extending longitudinally of the furnace for bridging the space between adjacent retorts, each of said tuyères having slidable supporting engagement with the respective adjacent walls of adjacent retorts, and means for sliding said tuyères at their said points of engagement with the retort, walls transversely thereof for causing the fuel bed to travel transversely of the retorts to the said ash receiving means.

8. In a furnace, a fuel bed support comprising a series of parallel retorts extending longitudinally of the furnace, adjacent retorts being spaced apart to provide passage of air upwardly between adjacent longitudinal walls of adjacent retorts from a point below the fuel bed, ash receiving means extending longitudinally of the furnace adjacent the outermost of said retorts, tuyères extending longitudinally of the furnace for bridging the space between adjacent retorts, each of said tuyères having slidable supporting engagement with the respective adjacent walls of adjacent retorts, and means for slid-

ing said tuyères simultaneously in the same direction at their said points of engagement with the retort, walls transversely thereof for causing the fuel bed to travel transversely of the retorts to the said ash receiving means.

9. In a furnace, a fuel bed support comprising a series of parallel retorts extending longitudinally of the furnace, adjacent retorts being spaced apart to provide passage of air upwardly between adjacent longitudinal walls of adjacent retorts from a point below the fuel bed, ash receiving means extending longitudinally of the furnace adjacent the outermost of said retorts, tuyères extending longitudinally of the furnace for bridging the space between adjacent retorts, each of said tuyères having slidable supporting engagement with the respective adjacent walls of adjacent retorts, and means for sliding said tuyères alternately in opposite directions, all of said tuyères moving together and in the same direction, the points of sliding being at their said points of engagement with the retort, walls transversely thereof for causing the fuel bed to travel transversely of the retorts to the said ash receiving means.

10. In an underfeed stoker, a group of longitudinally extending retorts, ash receivers at the opposite sides of said group of retorts and a plurality of tuyères operatively associated with said retorts and arranged in substantial horizontal alignment.

11. In an underfeed stoker, a group of spaced parallel longitudinally extending retorts, ash receivers at the opposite sides of said group of retorts and a plurality of tuyères bridging the space between said retorts and arranged in horizontal alignment.

12. In an automatic underfeed stoker of the multiple retort, side dump type, the combination with a pair of retorts, of a tuyère arranged therebetween and means for actuating said tuyère to shift the fuel laterally toward the side dumps.

13. In an automatic underfeed stoker of the multiple retort, side dump type, the combination with a plurality of retorts, of a plurality of tuyères operatively associated with said retorts and arranged in substantial horizontal alignment, and means for actuating said tuyères to shift the fuel laterally toward the side dumps.

14. In an underfeed stoker, a pair of retorts, ash receivers at the opposite sides of said pair of retorts and a plurality of tuyères

operatively associated with said retorts and arranged in substantial horizontal alignment, each retort being provided with a vertical wall, and a wall inclined to laterally shift the fuel toward the ash receiver adjacent thereto.

15. In an underfeed stoker, a group of retorts, ash receivers at the opposite sides of said group of retorts and tuyères operatively associated with said retorts and arranged in substantial horizontal alignment, one wall of each retort nearest its adjacent ash receiver having a greater inclination than the adjacent wall to laterally shift the fuel in the direction of the said ash receiver.

16. In an underfeed stoker of the side dump type, a group of longitudinally extending retorts, ash receiving and discharging devices at the opposite sides of said group of retorts and a plurality of tuyères operatively associated with said retorts and arranged in substantially horizontal alignment.

17. In an underfeed stoker of the side dump type, a group of transversely spaced longitudinally extending retorts arranged in substantially horizontal alignment, ash receiving and discharging devices at the opposite sides of said group of retorts and longitudinally extending tuyères operatively associated with the longitudinal edges of said retorts and bridging the space between said retorts.

18. In an underfeed stoker of the multiple retort side dump type, a group of longitudinally extending retorts arranged in substantially horizontal alignment for feeding fuel to a common bed, ash receiving and discharging devices at the sides of said bed and longitudinally extending tuyères operatively associated with the edges of said retorts and bridging the space between said retorts.

19. In an underfeed stoker of the multiple retort side dump type, a group of laterally spaced longitudinally extending retorts arranged in substantially horizontal alignment with the walls thereof continuous throughout their length, ash receiving and discharging devices at the opposite sides of said group of retorts and longitudinally extending tuyères engaging the longitudinal edges of said retorts throughout their length and bridging the space between said retorts.

In testimony whereof I affix my signature.

ROYCE L. BEERS.
